KNITTED FABRIC.

No. 20,213.

Patented Oct. 21, 1890

UNITED STATES PATENT OFFICE.

FRANK. L. WIGGIN, OF LOWELL, MASSACHUSETTS.

DESIGN FOR A KNITTED FABRIC.

SPECIFICATION forming part of Design No. 20,213, dated October 21, 1890.

Application filed September 23, 1890. Serial No. 365,908. Term of patent 14 years.

To all whom it may concern:

Be it known that I, FRANK. L. WIGGIN, of Lowell, in the county of Middlesex and State of Massachusetts, have invented a certain new and original Design for Knitted Fabrics, of which the following is a specification.

My design is fully shown in the accompanying photograph, and is portrayed in the white and lighter shaded figures.

10 The design consists, essentially, of lines of projecting pyramidal figures extending to or toward a point midway between the two figures thereabove.

What I claim as my design is—
The design for knitted fabrics, substantially 15 as herein shown and set forth.

In testimony whereof I have signed my name to this specification, in the presence of two subscribing witnesses, this 30th day of August, A. D. 1890.

FRANK. L. WIGGIN.
